BRAKE MECHANISM

Arthur F. O'Connor, Chicago, Ill., assignor, by
mesne assignments, to Union Asbestos & Rub-
ber Company, Chicago, Ill., a corporation of
Illinois

Application February 14, 1934, Serial No. 711,155

7 Claims. (Cl. 254—149)

My invention relates in general to brake-operating mechanism and has more particular reference to operating mechanism for railway car hand brakes.

5 An important object of the invention is to provide a winding mechanism of simplified construction facilitating assembly and hence reducing the cost of manufacturing the same.

Another important object is to provide a winding drum and associated gear for driving the same, said gear and winding drum being formed as an integral part for assembly in the winding mechanism, a further object being to form the winding drum with a helical winding track.

10 Another object is to construct the winding drum so as to quickly take up excess slack in the tension element or chain during the initial winding movement of the drum and thereafter gradually increase the tension force as the winding of the tension element on the drum progresses, a further important object being to form a winding drum having the aforesaid features and including an integral drum-driving gear of relatively light construction and consequently economical to 15 manufacture without sacrificing requisite strength to resist strains and rough usage to which the mechanism may be subjected during use.

Another important object is, in conjunction 20 with a pinion adapted for manual rotation as by a hand wheel and drivingly associated with a winding drum in a mechanism of the character mentioned in which the pinion has an associated ratchet, to provide a means in position to cooperate with the ratchet, including a pawl rotatable on a shaft and normally biased toward ratchet-engaging position wherein the shaft also 25 is rotatable and carries a pawl-tripping finger fixed thereon in order to cause the tripping finger to disengage the pawl from the ratchet when the shaft is rotated in one direction, a further object being to form the pawl-carrying shaft and the tripping finger as an integral element with one end of the shaft formed in non-circular fashion to fit into a corresponding non-circular opening in a manually operable handle whereby the 30 pawl may be assembled on the shaft and the same assembled as a unit in building the structure and the handle finally applied to the end of the shaft.

35 Numerous other objects and advantages will be apparent from the following description, which, taken in connection with the accompanying drawing, discloses a preferred embodiment of my invention.

40 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Figure 1 is a view in vertical section taken longitudinally through the end of a railway car showing a device embodying my present invention in operating position;

5 Figure 2 is a view in vertical section taken substantially along the line 2—2 in Figure 1 in order to show the internal construction of the device embodying my present invention;

10 Figure 3 is an enlarged perspective view of a combined winding drum and drum-driving gear forming a part of the device shown in Figure 2;

Figure 4 is a sectional view taken substantially along the line 4—4 in Figure 3;

15 Figure 5 is a view in horizontal section taken along the line 5—5 in Figure 2; and

Figure 6 is a view in vertical section taken along the line 6—6 in Figure 2.

20 To illustrate my invention, I have shown on the drawing a brake-operating mechanism adapted to be mounted in operating position as on the end of a railroad car 11, said mechanism including a housing 13 adapted to be secured to the wall of the car 11, and winding mechanism supported within the housing 13 and adapted to be manually operated as by means of the hand-wheel 15 in order to tension a flexible tensioning element, such as a chain 17. The tensioning element 17 is connected to the brake rigging of the car 11 in any suitable fashion. In the illustrated embodiment, it is attached to a draw rod 20

25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

46 The housing 13 may be of any suitable construction and is formed for attachment on the wall of the car 11. The casing comprises a preferably drawn sheet metal backing plate 31 and a cover 33, preferably formed as a casting, comprising a front wall having preferably integral means forming spaced side walls 35 and a preferably curved top wall 37, the free edges of said walls being formed for attachment to the backing plate in any convenient or preferred fashion,

55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100

so that the front of the cover is supported in spaced-apart relationship with respect to the backing plate to form a housing provided with an opening 39 opposite the curved wall portion 37. 5 The winding mechanism is supported within the housing between the backing plate and the front wall of the cover with the tension element 17 extending through the opening 39 in position to connect with the tension rod 19. The winding mechanism comprises a winding drum 41 and drum-driving gear 43 preferably formed as an integral element comprising a central bearing 45 having end portions 47 and 49 respectively opposite the drum 41 and gear 43 and adapted to 10 receive bushings 51 spaced at the opposite ends of the bearing 45 whereby to rotatably mount the element on a shaft 53. The opposed ends of the shaft 53 are secured respectively in the back plate 31 and in the front wall of the cover 33, said back plate and front wall having openings 55 of noncircular configuration to receive the correspondingly configurated ends of the shaft 53. The perforations 55 and the ends of the shaft 53 are preferably circular throughout 15 the major portions of their peripheries, the remaining peripheral portions being flattened as at 57 so that the flattened portions face upwardly in the assembly whereby the rounded portions of the perforations 55 may afford upward support 20 upon the ends of the shaft 53, while the shaft is prevented from rotating with respect to the casting walls by the interaction of the flattened portions 57. This arrangement is easy to effect and facilitates the assembly of the shaft and the 25 rotatable element thereon in the casing.

The backing plate 31 also is preferably dished inwardly toward the front wall of the cover 33 where the perforation 55 is formed in order to provide a strengthening embossment 59 in the 30 sheet metal backing plate. The bearing 45 also is preferably formed with an annular integral recess 61 between the end portions 47 and 49, which, if desired, may be loaded with a suitable lubricant, as by filling the space with absorbent 35 material saturated with oil in order to afford lubrication between the bushings 51 and the shaft 53.

The drum-driving gear 43 comprises a web 63 40 preferably extending in a plane intersecting the axis of the bearing 45 at right angles, the edge of the web 63 being formed with a peripheral rim 65 in which gear teeth 67 are formed. The winding drum comprises spaced web portions 69 45 formed helically with respect to the axis of the bearing 45 to define a helical winding space 71 between the webs 69 adapted to receive the tensioning element 17, one end of which is attached to an anchor pin 73 extending between the webs 69, which are formed as at 75 to provide support 50 bushings for the anchor pin. Where a chain is used as the tension element 17, the pin 73 is threaded through the end link of the chain as shown in Figure 2 of the drawing, said link lying with its plane extending between the planes of 55 the webs 69. The winding drum also is formed with webs 77 extending between the webs 69 and lying substantially in planes extending radially of the axis of the bearing 45.

The webs 77 extend from the bushings 45 outwardly to points within the peripheral edges of the web 69 for the purpose of strengthening the same and to define pockets 79 for receiving alternate links of the chain, including the end link which is anchored to the pin 73, the remaining 60 links of the chain extend with their planes sub-

stantially parallel with the axis of the bearing 45 and lie upon the outer edges of the webs 69, which are flattened to provide link-supporting surfaces extending at progressively decreasing distances measured vertically from the axis of the bearing 45 throughout the circumference of the winding drum, so that when the winding drum is turned in a counter-clockwise direction, viewing Figure 2 of the drawing, the chain will be wound upon the winding drum in a direction 10 to draw the rod 19 upwardly, viewing Figure 1, to actuate the brake rigging to set the brakes with progressively increasing force due to the decreasing distance between the chain links and the axis of the bearing 45 as the chain is wound 15 on the winding drum.

The webs 77 are extended as at 81 on one side of the winding drum to the web 63 of the drum-driving gear, said web extensions 81 being integral with the drum and the gear web in order to 20 strengthen the rotatable winding element.

The web 63 also is formed with perforations 83 in order to reduce the weight of the element and save material without sacrificing requisite strength and a perforation 85 is formed in the 25 web 63 in alignment with the anchor pin support openings 75 in order to facilitate the application of the anchor pin 73 between the webs 69 of the winding drum. This pin is preferably riveted in place permanently during the assembly 30 of the mechanism.

The drum-driving gear is drivingly associated with a gear-driving pinion 87 which is mounted in the upper portions of the housing 13, that is to say, the pinion 87 is mounted within the 35 curved wall portions 37 of the casing. The pinion 87 is also preferably formed as an integral part of a rotatable element 89, which is journaled for rotation in the back plate 31 and the front wall of the cover 33 and carries an integral 40 ratchet 91 formed thereon.

The element 89 is formed with a bearing portion 93 journaled in a bushing 95 inserted in a perforation 97 formed in the back plate 31 centrally of an embossed portion 99, which is formed 45 in the back plate for the purpose of strengthening the same at this point. The bushing 95 also is secured in place by means of an annular-anchoring element 101, which is seated in the embossment 99. The pinion 87 is preferably formed 50 in the element 89 adjacent the bearing portion 93 in position to register with the toothed periphery of the drum-driving gear 43, the ratchet 91 being arranged on the element 89 substantially opposite the winding drum 41. The element 89 also is 55 formed with a second bearing portion 103 journaled in a bushing 105, which, in turn, is mounted in a seat 107 formed in the front wall of the casing 33. The element 89 also has a preferably integral tapered shank 109 extending outwardly of 60 the front wall of the casing 33, said shank 109 being preferably squared to receive a correspondingly squared portion of the hand wheel 15, which is held in place on the shank 109 by means of a nut 111 secured on the threaded outer end 113 65 of the shank 109, the nut being retained in position in any suitable fashion as by means of a cotter pin 115.

The actuating mechanism also includes a pawl 117 co-operatively associated with the ratchet 91, 70 said pawl comprising a fitting rotatably mounted on a shaft 119, which is journaled for rotation at one end in a perforation formed in a dished portion 121 on the backing plate and which, at its other end is journaled in and extends through a 75

149

2,077,256

3

bearing 123 formed in the front wall of the cover, the shaft 119 has an end 125 projecting outwardly of the front wall casing and formed in a non-circular fashion preferably square to fit into a correspondingly formed opening at one end of a handle 127, by means of which the shaft 119 may be rotated in the casing.

The pawl 117 has a tip in position to engage the periphery of the ratchet 91, and means is provided to normally urge the tip of the pawl into engagement with said ratchet, said means preferably comprising a weighted projection 129, which may be conveniently arranged to swing in the space adjacent the pawl and opposite the pinion 15 so that the pawl is actuated by the gravitational effect upon the weighted portion 129, which is preferably formed integral with the pawl.

In order to raise the pawl from ratchet-engaging position, the shaft 119 carries a collar 131 fixed on the shaft adjacent the pawl, said collar having a pawl-raising finger 133 adapted to underlie the pawl so that as the handle 127 is moved in a counter-clockwise direction, viewing Figure 2, the pawl-actuating finger 133 will engage the underside of the pawl 117 and force it out of engagement with the ratchet against the normal urge of the weighted projection 129.

It will be noted that movement of the pawl 117 under the influence of the finger 133 will be limited by the curved top wall 31 so that the pawl and its projecting weight 129 cannot reach a position in which the weight 129 will urge the pawl in a direction away from ratchet-engaging position. The pawl-actuating finger 133 also is preferably formed so that it engages the pawl before the handle 127 reaches a vertical position.

Clockwise movement of the hand wheel 15, viewing Figure 2, imparts a counter-clockwise movement to the gear 43 and the winding drum 41. Such movement, when the drum is in brake-released position will cause the chain to be wound upon the helical winding groove of the winding drum with the link 161 adjacent the end link of the chain resting upon the flattened edges 163 of the webs 69, which are relatively remote from the winding center of the drum. As the chain is wound upon the drum, the links 165, 169, 173, and 177 will progressively engage and lie upon the flattened winding surfaces 167, 171, 175, and 179, which surfaces are progressively closer to the axis of rotation of the winding drum so that the center of the chain, during the rotation of the drum, moves inwardly toward the axis of the drum and consequently the tensioning force exerted on the chain becomes progressively greater due to the gradual reduction of the distance between the chain and the axis of the drum, so that force applied by the mechanism for the purpose of setting the brakes gradually increases as the slack is taken up.

One of the important advantages of forming the winding drum with a helical winding track is due to the fact that as the chain is wound upon the track in setting the brake mechanism, the upper end of the rod 19 will be carried outwardly away from the car body of the car 11. This movement will minimize the inclination imparted to the rod 19 as the bell crank 21 tilts during the brake-setting operation. The tilting of the bell crank 21 during brake-setting operation carries the lower end of the rod 19 outwardly away from the end of the car so that by employing a helical winding drum, the upper end is also carried outwardly with the result that the tilting of the rod 19 is minimized. This is of special advantage

when and if the housing 13 and the winding mechanism therein is located near the bell crank 21.

Furthermore, the slack is taken up more rapidly during the initial brake-tensioning movement of the winding drum, since the chain, during this initial movement, is wound more rapidly on the drum, since its center is disposed at a greater distance from the axis of the drum than is the case during the final brake-tensioning movement.

It will be noted that the handle 127, unless forcibly shifted, tends to remain in the position illustrated in Figure 2 of the drawing, thus permitting the pawl to normally engage the ratchet under the influence of the weight 129. As the hand wheel 15 is rotated in a clockwise direction, viewing Figure 2, in order to wind the chain 17 on the drum 41, the ratchet 91 will likewise be shifted in a clockwise direction, the pawl 117 seating in successive notches of the ratchet so as to prevent releasing movement when the hand wheel is released and holding the brakes in set position. When it is desired to release the brakes, it is only necessary to raise the handle 127 in order to disengage the pawl from the ratchet whereupon back tension in the brake rigging will rotate the winding drum in a clockwise direction and the pinion and ratchet in a counter-clockwise direction, viewing Figure 2, until the brakes are fully released.

If the handle 127 is released when to the right of the vertical plane through the axis of its pivot, its weight will return it to the position shown in dotted lines. The pawl likewise will return to ratchet-engaging position to automatically condition the apparatus for the brake-tensioning operation. If the handle, when released, is on the left hand side of a vertical plane through its pivot, its weight will urge it to a position pressing the pawl against the curved portion 37 of the casing out of ratchet-engaging position.

The construction is unusually simple and inexpensive to manufacture and the casing has inherent rigidity rendering it particularly well adapted to support the winding mechanism firmly and securely during rough usage to which such apparatus is subjected.

It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages, the form herein described being a preferred embodiment for the purpose of illustrating my invention; but I do not, herein, claim the novel features of the casing, per se, since the same comprises subject matter claimed in my co-pending application, Serial No. 711,154, filed of even date herewith, Patent No. 2,016,388, issued October 8, 1935.

Having thus described my invention, what I claim as new and desire to secure by Letters Patent is as follows:

1. A brake-operating mechanism comprising a rotatable winding drum having spaced webs forming a helical winding channel extending once around said drum with the opposed ends of the channel in staggered relationship, strengthening webs interconnecting the spaced webs, the peripheral portions of said spaced webs extending at varying distances from the axis of the drum, and a flexible element on said drum in position

to be wound up in said channel when the drum is rotated.

2. A brake-operating mechanism including a rotatable winding drum comprising an integral element including a hub, spaced webs extending from said hub and forming a helical winding channel extending once around the drum with the opposed end of the channel arranged in offset relationship, and a web forming a driving gear extending from said hub, strengthening webs on said hub interconnecting said gear and channel-forming webs, a flexible brake-operating member connected to said drum in position to wind in said channel when the drum is rotated, said member being secured on an anchor pin mounted in and extending between said channel-forming webs, and said gear-forming web having a perforation through which the anchor pin may be inserted into place between said channel-forming webs.

3. A winding drum comprising spaced webs forming a helical winding channel extending once around said drum with the opposed ends of the channel in overlapping relationship.

25 4. A brake operating mechanism including a chain, a chain winding drum comprising a hub and spaced webs on said hub forming a helical winding channel for receiving alternate links of the chain, driving means integral on said hub for turning said drum to wind the chain thereon, and strengthening webs interconnecting said spaced webs and said driving means, said helical winding channel having a pitch such that the

chain is wound upon said drum in the direction of the tensioning force on said chain.

5. A brake operating mechanism comprising a link chain, a chain winding drum comprising a hub and spaced webs on the hub forming a helical winding channel for receiving alternate links of the chain between said webs, the peripheral edges of said webs being formed to provide seats for receiving the remaining links of said chain laterally, means to turn said drum to wind the chain thereon along a path lying in a plane intersecting the axis of said drum at other than a right angle, the helical winding channel having a pitch such that the chain may extend in said plane after winding on said drum. 10 15

6. A brake operating mechanism including a link chain, a chain winding drum comprising a hub and spaced webs on said hub forming a helical winding channel for receiving alternate links of the chain between said webs and the remaining links laterally on the peripheral edges of said webs, said helical winding channel comprising one turn on the drum with the opposite ends of the channel in overlapping relationship. 20

7. A brake operating mechanism including a link chain, a chain winding drum comprising a hub and spaced webs on said hub forming a helical winding channel for receiving alternate links of the chain between said webs and the remaining links laterally on the peripheral edges of said webs, said helical winding channel comprising one turn on the drum the pitch of said channel being less than its width. 25 30

ARTHUR F. O'CONNOR.
